-5

Fig. 5

FIGURE 1 is a perspective view of an indicating gauge embodying my new design;

FIGURE 2 is a top plan view of the indicating gauge shown in FIGURE 1;

FIGURE 3 is a side view of the indicating gauge shown in FIGURE 1;

FIGURE 4 is a side view of the indicating gauge shown in FIGURE 1, but with the indicating member thereof pivoted to an alternate operative position;

FIGURE 5 is a sectional view taken on the line 5-5 of FIGURE 4; and,

FIGURE 6 is a fragmentary side view of the forward end portion of the gauge shown in FIGURE 1 but taken from the opposite side.

I claim:

The ornamental design for an indicating gauge, as shown.
